UNITED STATES PATENT OFFICE.

WALTER S. BALES, OF DES MOINES, IOWA.

GRADING AND EARTH-MOVING MACHINE.

1,254,191.

Specification of Letters Patent. Patented Jan. 22, 1918.

Application filed January 9, 1915. Serial No. 1,414.

To all whom it may concern:

Be it known that I, WALTER S. BALES, citizen of the United States of America, and resident of Des Moines, Polk county, Iowa, 5 have invented a new and useful Grading and Earth-Moving Machine, of which the following is a specification.

The object of this invention is to provide an improved construction for a grading and 10 earth-moving machine.

A further object of this invention is to provide an improved motor driven grading machine having one or more endless diggers mounted at and carried by the forward end 15 thereof.

A further object of this invention is to provide an improved motor driven grading machine having one or more digger heads mounted for lateral rectilinear reciprocation on the forward end thereof.

A further object of this invention is to provide an improved grading machine having an endless digger head mounted for altitudinal adjustment at the forward end 25 thereof.

A further object of this invention is to provide an improved frictional transmission for driving a grading machine.

A further object of this invention is to 30 provide an improved crumbing blade cooperating with the endless diggers.

My invention consists in the construction, arrangement and combination of elements hereinafter set forth, pointed out in my 35 claim and illustrated by the accompanying drawing, in which—

Figure 1 is a side elevation of my improved machine, dotted lines indicating an adjusted position of the lower portion of the 40 endless diggers. Fig. 2 is a front elevation of the same, dotted lines indicating folded position of the lateral conveyer extension.

In the construction of the machine as shown the numeral 10 designates a bed frame 45 carried at its rear end on a supporting and steering roller 11, through a yoke 12, and at its forward end on supporting and driving wheels 13, 14. A prime mover, such as a steam engine 15, is mounted on the rear 50 portion of the bed frame 10 and drives wheels 13 and 14 by any desired means capable of driving the wheels 13 and 14 in either direction. A steering rod 23 is journaled in the bed frame 10 and is provided with a hand wheel 24 at its upper end. A cable 25 is wound in its central portion on and fixed to the lower end of the steering rod 23 and

has its ends secured to opposite ends of the yoke 12, whereby the machine may be steered by oscillating the roller 11, the central portion of said yoke being pivoted to the frame 10 for oscillation on a vertical axis. Standards 26 are fixed to and rise from the bed frame 10 and a roof or canopy 27 preferably is fixed to and carried by said standards. 60

Standards 28 are fixed to and rise from the extreme forward end of the bed frame 10 and a bracket frame 29 is mounted thereon, extends forwardly, and is vertically slidable on said standards. Any desired means 70 may be employed for raising and lowering the bracket frame 29. For this purpose I have shown a shaft 30 journaled for rotation in the lower ends of the standards 28 and having a crank 31 on one end for manual rotation thereof. A bevel gear 32 is fixed to the shaft 30 and meshes with and is adapted to drive a bevel gear 33 fixed to a screw shaft 34 journaled for rotation in upright position between the standards 28. 75 The screw shaft 34 is threaded through the lower portion of the bracket frame 29 and is adapted in its rotation to raise and lower said frame and the elements carried thereby in a common manner. 80

Laterally spaced and connected digger heads 35, 36 are mounted on the bracket frame 29 and are adapted for transverse reciprocation thereon in front of the machine during the digging operation. The digger 90 heads 35, 36 preferably are mounted on rollers 37 riding on the bracket frame. Telescoping masts 38, 39 are fixed to and depend from the digger heads 35, 36 and endless diggers, designated generally by the numerals 40, 41, are mounted for travel on said heads and masts. The endless diggers here shown comprise endless sprocket chains carrying excavating devices, and are illustrated and described in detail in my companion application filed March 3, 1915, Serial Number 11,924, for ditching and earth-moving machine, to which application reference hereby is made. 95

A prime mover 42, here shown as a twin 105 cylinder steam engine, is mounted on a platform 43 carried by the digger heads 35, 36, and is supplied with steam by a pipe 44 from the boiler of the prime mover 15, said pipe being suspended by hangers 45 from the 110 roof 27, and formed at its forward end with a flexible portion or tube 44a. The crank shafts 42a of the engine 42 are connected by sprocket gearing 46, 47 to the endless dig-

gers 40, 41. A horizontal conveyer of any desired form, designated generally by the numeral 48, is mounted through but independent of the digger heads 35, 36 and is supported by standards 49 from the bracket frame 29. The horizontal conveyer 48 is adapted to receive earth from the endless diggers 40, 41 and deliver the same at one side or another of the machine. A shaft 50 is journaled for rotation in bearings 51 carried by the bracket frame 29 and extends beneath the conveyer 48. A bevel gear 52 is fixed to the inner end of the shaft 50 and is in mesh with and adapted to be driven by a bevel gear 53 fixed to a shaft 54 journaled in the bracket frame 29. A pulley 55 is fixed to the shaft 54 and is connected by a belt 56 to a pulley 17^a fixed to the crank shaft 17 and adapted to drive, through the said shaft 54 and bevel gears 53, 52, the shaft 50. The endless belt 56 passes beneath direction pulleys 57, 58 mounted for rotation in a pulley block 59, which pulley block is yieldingly connected by an expansive coil spring 60, to the frame 10. This yielding connection permits vertical movement of the bracket frame 29 as above described.

The horizontal conveyer 48 is driven by a sprocket chain 60 passing over a sprocket wheel 61 fixed to one of the conveyer shafts and over a sprocket wheel 62 on the forward extremity of the shaft 50.

The digging mechanism is adapted for bodily rectilinear reciprocation, during operation, transversely of the bracket frame 29, whereby the digging devices cut a path of approximately twice the width of the space between the outer extremities of the digging devices. Any desired means may be employed to accomplish this lateral oscillation of the digging mechanism. For this purpose I have shown a bevel gear 63 fixed to the shaft 50 and meshing with and adapted to drive a bevel gear 64 (dotted lines Fig. 1) fixed to a crank shaft 65 journaled for rotation in the bracket frame 29. The crank shaft 65 is connected by a pitman 66 to a wrist pin 67 in a cross member 68 connecting the digger heads 35, 36.

50 The lateral conveyer 48 may be provided with a pivoted extension 69 adapted to be folded out of the way at times as indicated by dotted lines in Fig. 2.

An arm 70 is pivoted by a bolt 71 to the lower end of the mast 38, which mast is adjustable as to length as described in my companion application above referred to. The arm 70, which preferably is formed of telescoping members adapted to be secured together by a set screw 72, carries on its free end sprocket wheels 73 adapted to engage the chains of the endless digger 40 at times, as shown by dotted lines in Fig. 1, to the end

of altering the angle of the excavating devices in their upward movement. This also obviates the necessity of removing a portion of the excavating devices when the telescoping masts are shortened. Any suitable means such as arms 76 (see Fig. 1) may be employed for setting and holding the arms 70 in position. It is to be understood that the arms 70 and sprocket wheels 73 are supplied for each of the masts 38, 39, although only one is shown in the drawing.

Arms 74 are fixed to the lower portion of the bracket frame 29 and project forwardly and downwardly toward the lower ends of the excavating devices. The arms 74 carry on their lower ends a crumbing blade 75 which extends laterally in front of the traction wheels 13, 14 and just at the rear of the lower ends of the excavating devices. It is the function of the crumbing blade 75 to catch loose earth which may be removed or dropped by the excavating devices and to collect, gather, carry and push forward such loose earth so that it may be taken up by the excavating devices at their lowest points of travel.

The prime advantage of this machine lies in the fact of carrying the endless digging devices ahead of the machine, so that the machine travels in the path as it is cleared, the earth being delivered to wagons or other conveyances at either side of the machine. The lateral oscillation of the digging devices permits the digging of a path considerably wider than such devices. It is to be understood that one or any number of digging devices may be employed; but it is deemed that two spaced diggers as shown are the most effective.

It is believed the friction drive is also a valuable feature of this machine, in that it admits of more perfect control of the speed.

I claim as my invention—

A digging machine comprising in combination a truck, a bracket frame mounted for vertical movement in advance of and carried by said truck, a frame mounted for reciprocation on said bracket frame and in a direction transverse to the body of the truck, means for reciprocating said reciprocating frame, a plurality of spaced endless digging devices mounted on said reciprocating frame, said digging devices cutting a path of greater width than said truck, and means whereby said bracket frame may be raised or lowered.

Signed by me at Des Moines, Iowa, this 17th day of June, 1914.

WALTER S. BALES.
